UNITED STATES PATENT OFFICE

104,517

DESIGN FOR A DRESS ENSEMBLE

Grace Diaz, New York, N. Y.

Application April 13, 1937, Serial No. 68,737

Term of patent 3½ years

To all whom it may concern:

Be it known that I, Grace Diaz, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The rear portion of the jacket unit is conventional.

The section seen through the lower portion of the sheer dress constitutes an attached underportion, which is ruffed as shown.

I claim:

The ornamental design for a dress ensemble, substantially as shown, and described.

GRACE DIAZ.
